UNITED STATES PATENT OFFICE.

DAVID F. CRAWFORD, OF PITTSBURGH, PENNSYLVANIA.

STOKER.

1,131,213.

Specification of Letters Patent.

Patented Mar. 9, 1915.

Application filed May 8, 1909. Serial No. 494,833.

To all whom it may concern:

Be it known that I, DAVID F. CRAWFORD, a citizen of the United States, residing at Pittsburgh, in the county of Allegheny and State of Pennsylvania, have invented certain new and useful Improvements in Stokers, of which the following is a specification.

The invention relates to automatic under-feed stokers, and has for its primary objects; the provision in apparatus of the character specified of improved means for regulating the feed through the feed trough; the provision of auxiliary feeding means in the trough whereby the supply of fuel to different portions thereof may be governed independent of the main feeding device; the provision of means whereby the stroke and feed of the auxiliary feeding means may be adjusted independent of the main feeding device; and the provision of an improved form of supporting means for the inner ends of the grate bars. Certain embodiments of the invention are illustrated in the accompanying drawings, wherein:—

Figure 1 is a longitudinal section through a furnace supplied with the improved stoker,

Figure 2 is a partial plan view of the apparatus,

Figure 3 is a section through the trough on the line III—III of Figure 1,

Figure 4 is a side elevation of the upper edge of the trough, showing the grate supporting frame,

Figure 5 is a partial longitudinal section through the end of a trough supplied with a modified form of plunger feed,

Figure 6 is a rear end elevation of the apparatus,

Figure 7 is an enlarged detail side elevation of the connection between the operating crank and the adjustable link,

Figure 8 is an enlarged detail rear elevation partly broken away, of the operating means for the adjusting link,

Figure 9 is an enlarged detail end view of the controlling handle and latch, and

Figure 10 is a longitudinal section through a furnace supplied with a modified form of auxiliary feed.

The stoker is illustrated as applied to a locomotive fire-box, but it will be understood that the construction is of general application and not limited to use in the relation shown. Only so much of the fire-box is

shown as is necessary to illustrate the relation of the parts.

Referring first to the general relation of parts as shown in Figs. 1 and 2; 1 is the firebox; 2 is one of the side grates which may be of any approved type, it being understood that the other side grate, not shown, is of the same construction; 3 is the front grate; 4 is the drop grate located at the end of the side grate 2, which drop grate is preferably somewhat inclined to the rear as indicated in dotted lines in Fig. 1; and 5 is the underfeed trough preferably of the general contour indicated in Fig. 1.

The primary feeding member is the piston 6 which is mounted for reciprocation beneath the hopper and is operated from the shaft 8 by means of the cranks 9—9 and the connecting rods 10—10. The shaft is oscillated from a steam cylinder 11 at the side of the fire-box by means of the crank arm 12 keyed to the shaft 8 and connected at its other end to the piston rod 13 of the steam cylinder.

Secondary or auxiliary feeding means are provided for the trough in the form of the two pistons or plungers 14 and 15 working in the manner indicated in Fig. 1, and arranged in tandem. The plungers are pivoted to the connecting rods 16 and 17, which connecting rods are pivotally secured at their other ends to the adjusting bars or links 18 and 19. The links 18 and 19 are operated from the shaft 8 by means of a crank 20, which crank is provided on each side with two projecting pins 21 and 22 (Fig. 7). The links 18 and 19 are provided upon their opposite faces with notches or recesses which are adapted to engage the pins 21 and 22. When the links engage the lower pins 22 a short stroke of the pistons or plungers is secured, and when the links are shifted upward to engage the pins 21 longer strokes are provided. The plurality of notches provides for a shifting of the position of the pistons or plungers backward or forward, a backward shifting of the pistons securing a less effective stroke as a smaller portion of the pistons is in this case forced into the fuel in the trough. The shifting also changes the position of supplemental feed.

The disengaging of the links from the pins in order to secure an adjustment is accomplished by means of the mechanism illustrated in detail in Figs. 7, 8 and 9. As here

shown, each of the bars 18 and 19 is engaged by loops or collars 23 and 24. These collars are pivotally engaged by crank arms 25 and 26 carried by the tube 27 and the rod 28 respectively. As indicated in Figs. 6 and 8, the rod and tube are extended laterally and provided at their ends with the operating levers 29 and 30. These handles are extended above the floor of the cab 10 and are provided with operating catches 31 adapted to engage notches in the rack 32 interposed between the two handles. The catches are operated from the upper ends of the handles by means of supplemental handles 15 provided with connecting rods as indicated in Fig. 9.

The ends of the grate bars constituting the grates 2 and 3 are pivotally supported at their ends upon the castings 34 illustrated in Figs. 3 and 4, which castings are rigidly bolted to the upper edges of the trough by means of studs or bolts extending through the downwardly projecting lugs 35. The upper edges of the castings 34 are recessed 25 for the reception of the ends of the grate bars, and the arrangement not only adds to the rigidity of the trough at its edges, but also permits of the ready removal of the parts for renewal or repair.

50 In some instances it may be desirable to retard the forward feed to the rear end of the trough, in which case the arrangement shown in Fig. 5 may be employed. In this construction the piston 15' employed is 55 directed rearwardly instead of forwardly as in the other form of device, and is reciprocated from the connecting rod 16' by means of the link 36 which is pivoted to the piston and to the rod 16'. This backward feed retard 40 tards the forward movement of the coal, and as a result the coal is banked up in front of the piston 15' and caused to spread laterally.

Still another modification is illustrated in Fig. 10, which modification differs from that of Fig. 1 in that only a single piston 15" is employed in the trough 5" instead of the pair of pistons. The construction in other respects is the same throughout as that heretofore described for the form of Fig. 1. In 50 this connection it will be understood that the invention is not restricted as to the number of auxiliary feeding plungers, but that any number may be used depending upon the conditions.

It will be seen from the foregoing that the feed through the trough may be much more accurately governed than in the old type of construction, wherein a single piston feed at the rear was depended upon to supply the fuel throughout the length of the furnace. 55 The amount of hand firing necessary is very much reduced, as the tendency of the coal in any portion of the trough to bank and distribute unevenly may be overcome by the operation of the pistons 14 and 15, which 60 pistons may be operated with a long or short stroke, depending upon the requirements, and may be entirely stopped if desired, by placing the bars 18 and 19 midway between the pins 21 and 22. The pistons or plungers 70 also serve to agitate the fuel, thereby breaking up the mass which may otherwise become compacted and thus securing not only a better forward feed, but also a better upward and lateral spreading. I am aware 75 that rods provided with agitators have heretofore been used in underfeed troughs, but such agitators differ from my feed plungers in that they do not produce a positive forward feed, but on each reverse stroke carry 80 the fuel rearwardly. They are furthermore incapable of adjustment without removing the body of coal in the trough, as opposed to my construction wherein the position and length of stroke may be adjusted at any time 85 to suit requirements.

Having thus described my invention and illustrated its use, what I claim as new and desire to secure by Letters Patent is the following:—

90 In combination in an underfeed stoker, a feed trough, a reinforcing member along the side edge of the trough and overlapping the top thereof and provided with recesses for receiving the ends of grate bars, 95 means for detachably securing the reinforcing member to the edge of the trough and against movement thereon, and grate bars constituting a side grate and having their inner edges supported in the said recesses.

100 In testimony whereof I have hereunto signed my name in the presence of the two subscribed witnesses.

DAVID F. CRAWFORD.
